UNITED STATES PATENT OFFICE.

FREDERICK J. DOLE, OF NEW YORK, N. Y., ASSIGNOR OF ONE-HALF TO HAROLD D. PENNEY, OF PELHAM, NEW YORK.

LIGHT-RAY-DIFFUSER SHADE FOR LAMPS.

1,199,767.

Specification of Letters Patent.

Patented Oct. 3, 1916.

Application filed February 23, 1912. Serial No. 679,445.

To all whom it may concern:

Be it known that I, FREDERICK J. DOLE, a citizen of the United States, residing in New York city, in the county of New York and State of New York, have invented certain new and useful Improvements in Light-Ray-Diffuser Shades for Lamps, of which the following is a specification.

The object of this invention is to provide a glow shade for vehicle lamps which will adequately illuminate the surface of the road, render the lamp visible for a long distance, and waste practically no illuminating power, while entirely doing away with the objectionable and blinding glare of unshaded lamps.

The invention constitutes an improvement upon lamp shades such as set forth in Letters Patent Reissue No. 12,983, granted to H. D. Penney *et al.* on June 29, 1909. In such device, a set of louvers is set forth, that are made of a totally opaque material, so that absolutely all of the rays that impinge upon these members and are not absorbed are deflected upon the surface of the road, which is brightly illuminated for a short distance, while the lamp and shade are almost invisible, or at least, as has been found in practice, not sufficiently visible.

In the present invention, the louvers are made of such a material or materials and so arranged that, while the downwardly inclined light-rays are not materially affected, the horizontal and upwardly inclined rays are diffused into glow rays, and while free from glare, are visible from a great distance and illuminate the adjacent road, objects, and the atmosphere with a mild radiance, and which will serve to illuminate and not dazzle.

In the accompanying drawings representing one embodiment of my invention, Figure 1 is a front elevation of the device, Fig. 2 is a vertical section, and Fig. 3 is a view showing one of the louvers broken away at the middle.

The device comprises a suitable frame or support member and a set or series of members extending across from side to side in the nature of louvers of long narrow thin plates which are inclined transversely to their width, and owing to their position and the nature of the transverse material employed, the light is diffused upon passage therethrough, and which, when viewed hori-

zontally or from above, substantially completely screen the lamps. The frame or support may be of any desired or suitable construction, and the louvers are preferably supported at their extremities only. These louvers are made of any desired or suitable material that is not opaque (which has been found to obstruct a certain amount of useful light rays and render the shade inadequate for roads where trees are low branching) or freely transparent which would not modify the glare, but is of a material of intermediate light properties, what is known as translucent. Louvers so constructed of such material will permit the passage of diffused horizontal rays and cause the more distant surfaces of the road to be illuminated, as well as illuminating the atmosphere and adjacent objects with a mild radiance, and thereby utilizing a greater portion of the total capacity of the lamps than heretofore. Such members may be made of any suitable material embodying these properties, which material preferably is such as not to be affected by the heat of such rays, or the heat radiating from the lamp. For instance the louvers could be constructed of mica, or of glass having a ground face or otherwise rendered translucent only, or of a form of celluloid or like material that would not be injuriously affected by heat, so that horizontal and perpendicular light-rays will be diffused by the louvers, or if they be made of glass, by their ground faces.

As indicated in Fig. 3 the louver is formed of superposed layers, that may be a layer of parchment paper or the like interposed between two layers of mica, the whole being properly translucent, and the inner mica serving to deflect indirect light-rays and cut off the heat rays and prevent the paper layer being injuriously affected and the paper to diffuse rays perpendicular thereto. These louvers are supported preferably at their ends, extend across the lamp, and are inclined downwardly and so offset or spaced that some or most of the forward rays will impinge upon the louvers and permit unobstructed downward passage upon the road surface of a certain portion of the light rays while upwardly inclined rays will be diffused, the shade will glow and be adequately visible and there will be no glare. It will be observed that the rays passing downwardly

from the lamp will most of them pass between these members and hence not be obstructed whereby the road immediately in front of the lamp, when used on a vehicle, 5 will be brightly illuminated. The louvers are horizontal and preferably of equal width, vertically alined, their vertical projections substantially screen the lamp and they slope in substantially parallel planes, which in- 10 cline downwardly from the device in the forward direction as shown.

The frame or supporting member as shown comprises a circular member or rim 5, that may be conical, as shown, and provided with 15 a bead 6 to strengthen the same. The frame is preferably made of sheet metal and may be formed by the stamping method. To secure the louvers to the frame the support or rim may be provided on each of the two 20 opposite sides with lugs or projections 7 and 8, to which the extremities of the louvers 9 are secured by any suitable means, such as rivets 10 passing through apertures in the louvers and in the lugs.

25 The support or rim may be secured to a lamp in any suitable manner or if desired made a portion of the lamp frame. As shown a projecting flange 12 is secured to the rear side of the rim that may be caused 30 to telescope on the front of the lamp.

Heretofore in order to comply with the ordinances requiring lamps of considerable brilliancy to have their glare entirely overcome, it has been generally necessary to pro- 35 vide a translucent sheet extending entirely across the front of the lamp such as ground glass. But by this arrangement, while the glare is overcome, so much of the light is absorbed that very little illumination is pro- 40 vided in front of the lamp. The purpose of the said reissue patent was to overcome this glare by cutting off the upward rays and to deflect the forward rays upon the road immediately in front of the lamp.

45 But with the present invention the advantages of the said patented device are retained, in that the illumination immediately in front of the lamp is not curtailed; while the rays that would be entirely obstructed 50 by its opaque louvers, are utilized to a great extent; they are diffused by the translucent louvers which change the glare of unshaded lamps, or the obscurity of lamps with opaque louvers, into a mildly radiant glow, visible 55 from afar, and cause adjacent objects to be lighted with a mild radiance, thereby using a larger proportion of the light generated by the lamp than is possible in shades made of opaque or non-diffusing materials.

60 Having described my invention I claim:

1. A light-diffusing lamp shade adapted to be located transverse to a light axis of a lamp and to illuminate without glare, by permitting the passage of light rays in- 65 clined from said axis in a particular direc-

tion and diffusing other light rays from said lamp and comprising a frame adapted to be secured to a lamp and a series of parallel louvers made of a non-heat conducting translucent material.

2. A light-diffusing lamp shade adapted to be located transverse to a light axis of a lamp and to illuminate without glare, by permitting the passage of light rays in- 70 clined from said axis in a particular direc- 75 tion and diffusing other light rays from said lamp and comprising a frame adapted to be secured to a lamp and a series of parallel louvers made of flexible translucent material.

3. A light-diffusing lamp shade adapted to be located transverse to a light axis of a lamp and to illuminate without glare, by permitting the passage of light rays in- 80 clined from said axis in a particular direc- 85 tion and diffusing other light rays from said lamp and comprising a frame adapted to be secured to a lamp and a series of parallel louvers made of flexible, non-heat-con- 90 ducting translucent material.

4. In a lamp shade, a support provided with a series of lugs on each side, and a series of louvers secured at their ends to said lugs to extend across one above the other and inclined downwardly, the louvers being of translucent material and spaced apart 95 to receive and diffuse part of the rays from the lamp without affecting other of the lamp rays.

5. In a lamp shade, a support provided with a series of lugs on each side and a series of louvers secured at their ends to said lugs to extend across one above the other and inclined downwardly, the louvers being of translucent material and spaced apart to receive and diffuse upward rays from the lamp 100 while permitting passage of substantially all of the downward rays.

6. In a lamp shade, a support provided with a series of lugs on each side, and a series of louvers secured at their ends to said lugs to extend across one above the other and inclined downwardly, the louvers being of translucent material and spaced apart to receive and diffuse the upward rays from the lamp and some of the forward rays while 105 permitting passage of substantially all of the downward rays.

7. In a lamp shade, a circular rim provided with a set of integral lugs on each side, and a series of louvers secured at their ends to said lugs to extend across one above the other and inclined downwardly, the louvers being of translucent material and spaced apart to receive and diffuse part of the rays from the lamp without affecting other of 110 115 the lamp rays.

8. In a lamp shade, a circular rim provided with a set of integral lugs on each side, and a series of louvers secured at their ends to said lugs to extend across one above the 120 125 130

other and inclined downwardly, the louvers being of translucent material and spaced apart to receive and diffuse upward rays from the lamp while permitting passage of 5 substantially all of the downward rays.

9. In a lamp shade, a circular rim provided with a set of integral lugs on each side, and a series of louvers secured at their ends to said lugs to extend across one above 10 the other and inclined downwardly, the louvers being of translucent material and spaced apart to receive and diffuse the upward rays from the lamp and some of the forward rays while permitting passage of 15 substantially all of the downward rays.

10. In a lamp shade, a circular rim provided with a series of integral lugs on each side, and a set of offset louvers of translucent material secured at their ends to said 20 lugs.

11. In a lamp shade, a metallic support provided with a series of integral lugs on each side, and a set of louvers secured at their ends to said lugs, the louvers being of 25 translucent material and spaced apart to receive and diffuse a part only of the rays from the lamp.

12. A light-diffusing lamp shade adapted to be located transverse to a light axis of a 30 lamp and to illuminate without glare, by permitting the passage of light rays inclined from said axis in a particular direction and diffusing other light rays from said lamp and comprising a frame adapted to be secured to a lamp and a series of parallel louvers inclined to and substantially conterminous parallel to said axis and made of 35 flexible translucent material.

13. A light-diffusing lamp shade adapted 40 to be located transverse to a light axis of a lamp and to illuminate without glare, by permitting the passage of light rays inclined from said axis in a particular direction and diffusing other light rays from said lamp 45 and comprising a frame adapted to be secured to a lamp and a series of parallel louvers inclined to said axis, and made of flexible translucent material.

14. A light-diffusing lamp shade adapted 50 to be located transverse to a light axis of a lamp and to illuminate without glare, by

permitting the passage of light rays inclined from said axis in a particular direction and diffusing other light rays from said lamp and comprising a frame adapted to be secured to a lamp and a series of parallel louvers inclined with and substantially conterminous parallel with said axis and made with smooth backs of flexible, non-heat-conducting, translucent material. 55

15. A light-diffusing lamp shade adapted to be located transverse to a light axis of a lamp and to illuminate without glare, by permitting the passage of light rays inclined from said axis in a particular direction and 60 diffusing other light rays from said lamp and comprising a frame adapted to be secured to a lamp and a series of parallel louvers made of celluloid.

16. The combination with a lamp of the 70 class described, of a plurality of louvers superposed one above the other in substantially the same plane at the front of said lamp, each composed of flexible translucent material for diffusing certain of the light 75 rays from such lamp.

17. A light-diffusing lamp-shade adapted to be located transverse to the light axis of a lamp to permit the passage of light rays inclined from said axis in a particular direction, and diffusing other light rays from said lamp, said shade being adapted to be secured to a lamp at the front thereof, and comprising a series of louvers superposed one above the other in substantially the 85 same plane, each made of flexible translucent material.

18. A light-diffusing lamp shade adapted to be located transverse to a light axis of a lamp and to illuminate without glare, by 90 permitting the passage of light rays inclined from said axis in a particular direction and diffusing other light rays from said lamp and comprising a frame adapted to be secured to a lamp and to a series of parallel louvers made of flexible non-heat-conducting 95 material.
